United States Patent Office

Des. 215,939

Patented Nov. 11, 1969

215,939

LAMP

John J. Vetere, Beverly, Mass., assignor to Sylvania Electric Products Inc., a corporation of Delaware

Filed Mar. 7, 1968, Ser. No. 10,882

Term of patent 14 years

Int. Cl. D26—01

U.S. Cl. D26—8

FIG. 1

The dominant features of my design reside in the full line portions.

I claim:

The ornamental design for a lamp, as shown and described.
